United States Patent Office

Des. 218,754

Patented Sept. 22, 1970

218,754

TRANSMITTER

Darrel A. Lauer, San Mateo, Calif., assignor to Ampex Corporation, Redwood City, Calif., a corporation of California

Filed June 16, 1969, Ser. No. 17,733

Term of patent 14 years

Int. Cl. D14—04

U.S. Cl. D26—14

The figure is a top, front and left side perspective view of a transmitter showing my new design, the right side being a mirror image of the left side, and the back and bottom being conventionally plain.

I claim:

The ornamental design for a transmitter, substantially as shown and described.
